UNITED STATES PATENT OFFICE.

LEOPOLD F. HEPTNER, OF JOHNSTOWN, PENNSYLVANIA.

RAIL CLAMP.

Application filed March 20, 1924. Serial No. 700,592.

To all whom it may concern:

Be it known that I, LEOPOLD F. HEPTNER, a citizen of the United States, residing at Johnstown, in the county of Cambria and State of Pennsylvania, have invented certain new and useful Improvements in Rail Clamps, of which the following is a specification.

The present invention relates to rail clamps especially adapted for use on mine ties.

An object of the invention is to provide reversible clamps to permit expeditious change if the portion of the clamp, which impinges the rail base, breaks or is otherwise rendered unsuitable for use.

Another object of the invention is to provide rail clamps the rail base impinging portions of which are detachable to permit removal of the same and replacement without changing the position of the rail or tie.

Other objects of the invention will be apparent from the following description of the present preferred forms of the invention taken in connection with the accompanying drawings wherein:

Fig. 1 is a plan view of a rail clamp constructed in accordance with this invention illustrating its application;

Fig. 2 shows a clamp in side elevation on one side of a rail and in vertical section on the opposite side of the rail, a portion of the tie being broken away to disclose details; and

Fig. 3 is an end elevation of the rail clamp illustrating its application.

In the drawings, in order to illustrate the application of this invention a mine tie 5 is shown which may be of conventional design and which has a rail 6 superimposed thereon in a manner well known in the art. The rail clamp constructed in accordance with this invention as shown in Figs. 1, 2 and 3 consists of a threaded shank 7 one end of which has an elongated head 8 formed thereon. The shank 7 is engageable through a complementary opening formed in the top of the tie 5 adjacent the base flange of the rail. The head engages the bottom face of the top of the tie 5. The portion of the clamp which impinges on the base flange of the rail consists of a body 9 which is in

the present instance shown to be of rectangular configuration and has lugs 10 projecting therefrom at diametrically opposite points. 55 The lower faces 11 of the lugs are bevelled or inclined so as to conform to the contour of the upper faces of the base flange of the rail. It will be noted that the lugs 10 are appreciably spaced from the opposite sides 60 of the tie 5 to permit the base flanges of the rail to be conveniently engaged beneath said lugs and likewise to permit rotative movement of the body 9 on its shank without changing the position of the rail on the tie. 65

The body 9 and shank 7 are provided with openings which are adapted to align for the reception of a cotter pin 12. The cotter pin prevents rotative movement of the body 70 9 on its shank in an apparent manner.

In use of the clamp it is manifest that the body 9 is threaded on the shank 7 until one of the lugs 10 impinges on the upper face of the base flange of the rail. 75 The cotter pin 12 is then engaged through the body and shank. It is of course to be understood that if desired or found necessary a plurality of corresponding openings may be formed in the body 9 and shank 7 80 so that the body may be tightened up when desired and still locked by the cotter pin. When one of the lugs 10 wears out, breaks off or the like, the body 9 may be rotated on the shank 7 until the opposite lug engages the base flange of the rail. 85

Obviously, various changes may be made in this device especially in the details of construction, proportion and arrangement of parts within the scope of the claims here-to appended.

What is claimed is:

1. A rail clamp for mine ties including a shank engageable through the tie and equipped with a body engageable with the shank, said body including a pair of projections and being rotatable while in operative position on the tie to urge either of said projections into engagement with the rail base. 95

2. A rail clamp for mine ties including a headed shank engageable through the bottom of the mine tie to dispose the shank above the top of the latter, and a clamping

body threaded on said shank and including a pair of lugs either of which is engageable with the base flange of the rail.

3. A rail clamp for mine ties including a headed shank engageable through the tie to dispose said shank above the top of the latter, a clamping body threaded on said

shank and embodying a pair of lugs either of which is engageable with the base flange of the rail, and means engageable through 10 said body and shank to lock said body from movement.

LEOPOLD F. HEPTNER.
